FORMING MACHINE

William C. Van Dresser and Wesley B. Van Dresser, Detroit, Mich., assignors to Van Dresser Specialty Corporation, Detroit, Mich., a corporation of Michigan

Application January 2, 1934, Serial No. 704,817

32 Claims. (Cl. 140—71)

This invention relates to a forming machine and has particular reference to a machine for bending wire or the like into a desired shape.

One of the primary objects of this invention is to provide a machine of the above mentioned character which will impart desired bends to a wire at spaced points throughout the length thereof without subjecting the portions of said wire between said spaced points to any bending action whatever.

More particularly the invention provides a machine for reversely bending or crimping a strip of wire or the like at spaced points throughout the length of the wire to form a flexible pad or mat in strip form. The reverse bends or crimps in the wire constitute the longitudinal edges of the strip or mat formed and these bent portions of the wire are connected by straight sections of the wire which extend transversely of this strip. It is a feature of the machine that mats or strips of any desired width may be formed and that the straight portions of the wire extending transversely of the mat will be wholly free from any permanent sets and will thus be extremely flexible.

A further object of the invention is to provide a machine for forming a mat or strip of the above mentioned character in which the fullness of the transverse sections of the mat may be varied to thus vary the flexibility of the mat or pad as a unit.

The invention provides further means for adjusting the degree of bending imparted to the wire to the end that the transverse sections of the mat may be caused to lie closer together or further apart as desired.

Numerous other objects and advantages of the invention will become more apparent as the following description proceeds particularly when reference is had to the accompanying drawings wherein.

Figure 1 is a top plan view, with parts broken away, of a machine constructed in accordance with the teachings of this invention;

Figure 2 is a transverse sectional view taken substantially on the line 2—2 of Figure 1;

Figure 3 is a vertical sectional view taken substantially on the line 3—3 of Figure 2;

Figure 4 is a fragmentary sectional view taken substantially on the line 4—4 of Figure 2;

Figure 5 is a detail perspective view of a portion of the machine showing the positions that certain parts of the machine assume during a portion of the operation of the machine;

Figure 6 is a view similar to Figure 5 showing

the parts of the machine during another portion of the operation thereof;

Figure 7 is a detail sectional view of one of the elements of the machine;

Figure 8 is a fragmentary horizontal sectional view taken substantially on the line 8—8 of Figure 2;

Figure 9 is a fragmentary horizontal sectional view taken substantially on the line 9—9 of Figure 2;

Figure 10 is a transverse sectional view taken substantially on the line 10—10 of Figure 8;

Figure 11 is a fragmentary vertical sectional view taken on the line 11—11 of Figure 2;

Figure 12 is a transverse sectional view taken substantially on the line 12—12 of Figure 1;

Figure 13 is a fragmentary vertical sectional view taken substantially on the line 13—13 of Figure 1;

Figure 14 is a fragmentary sectional view taken substantially on the line 14—14 of Figure 2;

Figure 15 is a fragmentary end elevational view of the structure shown in Figure 12;

Figure 16 is a detail perspective view of one of the elements of the machine;

Figure 17 is a detail perspective view of a member which cooperates with the members shown in Figure 16;

Figure 18 is a fragmentary sectional view taken substantially on the line 18—18 of Figure 2; and

Figure 19 is a fragmentary plan view of the crimped wire strip or pad formed by the machine.

In application Serial Number 683,663, entitled "Spring cushion" and filed by William C. Van Dresser, there is disclosed a mat adapted to be interposed between the coil springs of a spring cushion and the upholstered cover pad thereof to prevent the pad from working down into the centers of the coil springs of the unit or into the spaces between the coil springs.

The construction disclosed in the said application comprises a crimped strip of wire and helical springs extending longitudinally of the crimped strip and secured to the edges thereof. The machine forming the subject matter of this application is adapted to form the crimped strip of wire for use in the construction of mats such as disclosed in said application No. 683,663.

A fragment of a crimped strip of wire or mat adapted to be formed by a machine constructed in accordance with the teachings of this invention is disclosed in Figure 19. By reference to this figure it will be noted that the wire 20 has formed therein at spaced points throughout its length the reverse bends 21, these reverse bends

being connected by straight sections of the wire, these latter sections being designated by the reference character 22. It is important in forming a mat of this character that the straight portions 5 22 of the wire be not subjected to any bending stresses whatever during the forming operation, since each time a wire is bent it receives a partial set and becomes less resilient. Thus the present 10 invention contemplates the provision of a machine in which the reversely bent portions 21 may be formed in the wire with practically no handling whatever of the intermediate straight portions 22. Further, it is important that means be provided for adjusting the amount of bend 15 imparted to the reversely bent portions 21 to thus regulate the spacing of the transverse members 22 longitudinally of the strip or mat. Therefore, the present invention provides a machine in which the degree of bending imparted to the 20 wire may be readily adjusted. Still further, it is important in the construction of a mat such as that illustrated that the fullness of the cross wires 22 be regulated and therefore the present invention provides means for accurately controlling the 25 bowing of these portions of the wire during the bending or forming operation. Having thus briefly outlined some of the many objects of the present invention, reference is now made to Figures 1 to 18 inclusive of the drawings wherein a machine capable of accomplishing the above and numerous other results is described.

Referring more particularly to Figure 2, it will be noted that the machine comprises a base 25 suitably supported in spaced relation to the floor 35 by legs or the like 26. Supported on the base 25 are two substantially inverted U-shaped frames designated by the reference characters 27 and 28. These frames are spaced from each other and outwardly from the center of the machine to provide 40 between them a space for receiving certain parts of the machine as will hereinafter be more fully described. Each inverted U-shaped frame comprises vertical legs 30 and 31, these legs being connected by a horizontal base 32. To aid in 45 describing the machine, the word "inwardly" will be utilized to mean toward the center of the machine as viewed in Figure 2, while the word "outwardly" will be used to indicate away from the center as viewed in Figure 2. Thus the legs 50 30 are the inner legs of the U-shaped frames, while the legs 31 are the outer legs thereof.

Journalled in the legs 30 and 31 and adjacent the base 25, is a main drive shaft 33 comprising axially aligned shafts 34 and 34' connected together with shearable pins 35 carried by flanged members secured to the adjacent ends of the shafts. If desired, hardened sleeves 35' may be inserted in the flanges to insure prompt severance 60 of the pins in the event any of the movable parts of the machine become jammed. This shaft may be driven in any desired manner by a suitable motor or the like (not shown). Also journalled in the legs 30 and 31 and extending parallel to the shaft 33 and above the same is an auxiliary shaft 65 36, this shaft being driven from the shaft 33 by suitable reduction gearing designated generally by the reference character 37. This shaft carries practically all of the driving mechanism of the machine as will hereafter become more apparent.

Journalled in the legs 30 and spanning the space between the two inverted U-shaped frames, is a shaft 40. This shaft is rotatably driven with a step by step movement by an indexing means 75 shown more clearly in Figures 2 and 11 of the

drawings. By reference to these figures it will be noted that there is secured to the shaft 36 by means of a pin 41, an eccentric 42. Embracing this eccentric so as to be actuated thereby is a strap 43, this strap being extended to form an arm 44 which carries at its upper end a pawl 45, this pawl being urged by a spring 46 into engagement with teeth 47 on a ratchet wheel 48 which is secured to the shaft 40. A pin 49 is carried by the arm 44 and engages in a slot in the pawl 45 to hold the pawl against rotation and to thus hold the toothed end of the pawl in proper relation to the teeth 47. For holding the arm 44 in such a position that the pawl 45 will engage the teeth 47, there is provided an arm 50 having its one end rotatably journalled on the shaft 40 as at 51 and having its other end rotatably journalled on a pin 52 which is carried by the free end of the arm 44. For preventing backward movement of the ratchet wheel 48 there is provided a pawl 53 which is urged into engagement with the teeth 47 by the spring 54. This pawl 53 is carried by a supporting bracket 55, the ends of this bracket rotatably receiving the shafts 36 and 40.

With this structure it will be apparent that 25 upon each rotation of the shaft 36, the arm 44 will be reciprocated to advance the ratchet wheel 48 and thus the shaft 40 a definite amount. Obviously, the amount of rotative movement imparted to the shaft 40 at each movement thereof 30 will depend upon the throw of the eccentric and the spacing of the teeth 47.

The shaft 40 carries and rotates the forming drums 56 and 57. These drums are similar in construction except of course, that one is a right hand drum while the other is a left hand drum. In view therefore, of the similar construction of these drums, the structure of one only will be described.

Referring then particularly to forming drum 40 57, this drum is secured by bolts 60 to a hub 61. Rotative adjustment of the drum with reference to the hub is provided by threading the bolts 60 into the drum as at 62, the bolts passing through circumferentially extending slots 63 in the hub. 45 The hub is keyed to the shaft 40 as at 64 for adjustment longitudinally thereof and may be secured in adjusted position by pin 65.

As illustrated in Figures 2 and 3, the drum is provided with radially arranged pins 66. These pins are slidably mounted in bores 67 formed in the drum and are normally urged inwardly toward the axis of the drum by springs 68. To provide for this inward movement of the pins, the outer face of the drum is recessed centrally as at 69, the inner ends of the pins projecting into this recess. Detachably secured to the outer end of each pin 66 is a forming pin or member 70, the detachable connections providing for the ready 60 substitution of forming members of different sizes.

For limiting inward movement of the pins 66, there is provided a cam member 75 which is bolted to the adjacent portions 30' of the inner face of the adjacent leg 30. The major portion of the periphery of the cam member 75 is concentric with the axis of the drum 57 and is so spaced inwardly from the periphery of the drum that when the pins ride on this part of the cam, members 70 do not project beyond the periphery of the drum. Through a predetermined portion of its periphery, however, the cam member is provided with a raised cam surface 76 which holds the pins in such a position that the ends 70 thereof project beyond 75

the periphery of the drum as clearly illustrated in Figure 3 of the drawings.

For raising the pins so that the lower ends thereof will rest on the surface 76, there is provided a member shown in detail in Figure 17 of the drawings, this member being designated by the reference character 71. This member is an elongated arm having a slot 78 through which the shaft 40 extends. At its lower end the arm 71 carries a roller 79 which rides on a cam 80 formed on the shaft 36. Adjacent its lower end the arm 71 is provided with a shoulder 81 which is engaged by a spring pressed plunger 82 carried by the adjacent portion of the adjacent leg 30. It will be apparent that the plunger 82 constantly tends to force the arm 71 downwardly and thus holds the roller 79 thereof in engagement with the cam 80.

As indicated in Figure 3 of the drawings, the portions 30' of the leg 30 to which the cam member 75 is secured are spaced to provide a way 85 in which the arm 77 may vertically reciprocate. It will be understood that the major part of the arm 77 lies in the plane of the portions 30' of the member 30 and thus slides on the outer face of the cam member 75.

At its upper end the member 11 is provided with an inwardly projecting portion 86 which slides in a groove 81 formed on the outer face of the cam member 15, this groove being immediately in advance of the surface 16 of the cam member. The portion 86 of arm 11 is provided with a cam surface 88 shown more clearly in Figures 3 and 17 of the drawings, this surface being adapted to engage the lower ends of the pins 66 to raise the same onto the surface 16.

The drum 57 is provided on its periphery and adjacent its inner edge with an annular band 99. This band is rotatably adjustable with reference 40 to the forming drum, this adjustment being provided by bolts 91 which pass through elongated slots 92 in the drum and which are threaded as at 93 in the band. The band carries on its outer periphery pins 94, these pins being adapted to 45 limit bowing of the wire as will hereinafter be more fully described.

As brought out before, the drums 56 and 57 are similar in construction and it will be apparent from the foregoing description that during operation of the machine the shaft 40 and thus the forming drums are rotated with a step by step movement. The drums carry forming pins which are normally retracted radially of the drums so that their outer ends are substantially flush with the peripheries of the drums. As the drums rotate however, the pins are successively elevated and held in elevated position during a predetermined portion of the rotation of the drum, this period being determined by the length of the cam surfaces 76. The pins 66 of the drum 57 are staggered with reference to the pins 66 of the drum 56 as clearly illustrated in Figure 1 of the drawings. Further, the cams 80 are oppositely positioned so that during actuation of the machine the pins are alternately elevated. Thus, for example, a pin 66 of drum 57 will be elevated and moved into engagement with its associated cam surface 76 and then at the next indexing movement of the drums, a pin 66 of the drum 56 will be elevated and moved into engagement with its associated cam surface 76. The manner of this operation and the reason therefor will become more apparent as the following description proceeds.

Associated with each forming drum are recip-

rovable jaw members adapted to embrace each pin 70 shortly after it is elevated to crimp or bend the wire around the same. Since these jaw members and their actuating mechanisms are similar in construction although opposite, one only will be described in detail. 5

Referring then first to Figure 2 of the drawings, it will be noted that the portion 32 of the inverted U-shaped frame 28 is provided with an elevated portion 100. Bolted or otherwise secured to the upper surface of this portion 100 is a plate 101 as illustrated in Figure 1 of the drawings. Secured to the upper face of this plate as by bolts or the like 102 shown in Figures 8 and 9 of the drawings, are members 103 and 104 which together form a guide-way for the reciprocating block 105. It will be noted that this block reciprocates in such a direction that it moves inwardly and outwardly with reference to the center of the machine and thus with reference to the forming drum with which it is associated.

Pivots secured intermediate their ends to the block 105 as by pivot pins 106 are jaw members 107. The inner ends of these jaw members carry rollers 108 adapted to engage the wire to bend 25 the same around the forming pins 70 as clearly illustrated in Figure 9 of the drawings. The jaw members are normally held apart by a spring 109 being urged toward each other against the force exerted by the spring by a wedge member 110 30 which engages the outer ends of the jaws. It will be noted that when the jaw members are moved outwardly as illustrated in Figure 8 of the drawings, the roller carrying inner ends thereof are in spaced relation to each other and out of the 35 path of travel of the pins 70. When, however, the jaw members are moved inwardly, as illustrated in Figure 9, the wedge engages the outer ends of the jaw members urging the inner roller carrying ends thereof toward each other. Further at this 40 time the jaw members have been moved inwardly sufficiently to embrace the pin 70 then in the path of their reciprocatory movement.

The wedge member is adjustable to vary the actuation of the jaw members and for this purpose the wedge member is carried on a shank 115 which passes through an elongated slot in block 105 and which is integral with a base 116 which is slidable in a groove 117 formed in the plate 101. The base 116 threadedly receives the end of 50 an adjusting screw 118 this screw being rotatably mounted in a bore in the plate 101 and being held against longitudinal movement in this bore by a pin 118' as clearly illustrated in Figures 2 and 9 of the drawings. It will be apparent that by rotating the screw 118, the base of the wedge member may be moved longitudinally of the groove 117 to thus adjust the position of the wedge member with reference to the outer ends of the jaw members. 55 60

For reciprocating the block 105, there is secured to this block a strap 120 and this strap carries at its outer end a roller 121 which is received in a cam groove 122 formed in a disc 123. This disc is secured to a supporting member 124 which is 65 fixed to a vertical shaft 125, this shaft being journalled in a portion 32 of the frame 28 and in a bearing 126, which projects inwardly from the leg 31 of the frame. The shaft 125 carries at its lower end a bevel gear 127 which is engaged by a bevel 70 gear 128 carried by the shaft 36.

As brought out before jaw members are associated with both forming drums. The jaw members are, however, oppositely actuated so that when one set of jaw members is in its innermost 75

position, the other is in its outermost position as clearly illustrated in Figure 1 of the drawings. This opposite actuation of the jaw members is of course, effected by properly designing the cam discs 123, as also clearly illustrated in Figure 1 of the drawings.

For positioning the wire to be formed with reference to the forming pins 70, there is provided an oscillating arm 130. This arm is pivotally supported at its one end in a block 131 which is supported from the frames 27 and 28 by a suitable strap 132. This structure is clearly shown in Figures 1 and 3 of the drawings. Throughout the major portion of its length the arm 130 is bifurcated and embraces and rides on a supporting guide bar 135. This bar is secured at its ends to plates 136 supported by standards 137 from the portions 100 of the frames 27 and 28.

For oscillating the bar 130, there is provided a rod 140, the length of this rod being adjustable by a turn buckle 141 located intermediate the ends of the same. At its one end the rod 140 is pivotally secured to the bar 130, while at its other end the rod is secured to a disc 142 which is fixed to an extension of shaft 125 which is associated with the frame 28. This structure will be more clearly understood by reference to Figures 1 and 2 of the drawings. The connection between the rod 140 and the disc 142 may be adjusted radially of the latter by virtue of the slot 143 formed in the disc. It will be apparent that the turn buckle 141 and the slot 143 provide means for varying the movement of the arm 130 incident to rotation of the disc 142. By shortening or lengthening the rod 140 by means of the turn buckle, the whole path of travel of the arm 130 may be shifted laterally or transversely of the machine. In other words, the arm may be caused to move closer to one side of the machine or the reverse of this. By adjusting the rod radially of the disc 132 in the slot 143, the extent of the movement of the arm 130 may be adjusted to thus cause the free end thereof to sweep a longer or shorter path, as desired.

Referring now to the free end of the arm 130, it will be noted that by reference to Figures 5 and 7 of the drawings this end of the arm carries a vertically disposed bushing 150 and that this bushing is bored to receive a pin 151. A spring 152 disposed within the bushing engages a shoulder on the pin to normally urge the pin downwardly beyond the lower end of the bushing to the position shown in dotted line in Figure 7. Downward movement of the pin 151 is limited by a cross arm 153 which is carried by the upper end of the pin 151, this cross arm engaging in a notch 154 in the upper end of the bushing when the pin is in its lowermost position.

The cross arm 153 serves a second purpose in that it provides means by which the pin may be elevated against the force exerted by the spring 152. For this purpose the cross arm 153 is extended and has its one end disposed between pins 155 carried by the end of the arm 130 with the result that the cross arm is prevented from rotation and is held in a position coincident with the longitudinal axis of the arm 130.

Engageable with the cross arm 153 are cam members 160, one of these cam members being secured to the upper face of each of the plates 136. It will be noted that the cam members 160 are adjustable toward and away from the center of the forming machine by virtue of the slots 161 formed in the body portions of these cam

members, the securing bolts 162 passing through these slots.

By reference to Figures 1 and 5 of the drawings, it will be noted that the cam members 160 are so positioned that each time the arm 130 approaches the end of its oscillatory movement, the cross arm 153 is engaged by one or the other of the cam members and the pin 151 is thus elevated to the position shown in full lines in Figure 7 of the drawings. This elevation of the pin 151 releases the engagement of this pin with the wire as will hereinafter be described.

After the wire has been formed to the shape indicated in Figures 1 and 19, the strip thus formed leaves the machine from the rear end 163 thereof travelling down a trough 165. This trough is hingedly secured to the frame members 27 and 28 as at 166 and is yieldably held in a predetermined inclined position by means of a spring 167 which is secured to the trough and surrounds the block 131 which constitutes the pivotal support for the arm 130.

The trough 165 extends to a point adjacent a reel 170 on which the formed strip of wire is adapted to be wound. To prevent the adjacent convolutions of the strip of wire wound on the reel from becoming hooked together, a strip of paper is wound between each convolution of the strip of wire. The structure for accomplishing this result is shown in Figures 2, 3 and 13 and by reference to these figures it will be noted that suitably journaled on a shaft 171 disposed below the base 25 is a roll of paper 172. The paper from this roll passes upwardly over the base 25 and then rearwardly below the chute 165 and to the reel 170. As the reel is rotated, the strip of paper is wound thereon and the strip of formed wire is also wound thereon between each convolution of the paper. It might be noted that the operation of winding the strip of wire on the drum is started by first fastening one end of the strip of paper to the reel and then rotating the reel, the strip of wire being picked up by the paper and carried with the same around the reel as the latter rotates.

The reel 170 is, as illustrated in Figures 12 and 13, supported on a standard 180 by means of a shaft 181 which is journaled in this standard. A set screw 182 engaging the periphery of the shaft 181 frictionally restrains the same against rotation to prevent reverse rotation of the reel.

At its one end the reel is preferably slidably keyed to the adjacent end of the shaft 181 as indicated by the reference character 183. The other end of the reel carries a stub shaft 184.

Loosely mounted on the shafts 181 and 184 so as to rock thereon is a yoke formed of the arms 185 and 186 and the cross member 187. Leg 186 of this yoke carries a pawl 188 adapted to engage a ratchet wheel 189 on the shaft 181 so that upon rocking of the yoke the shaft 181 and thus the reel or roll 170 is rotated.

It constitutes a feature of this invention that the amount of rotation of the roll 170 is varied as the diameter of the roll of formed wire wound thereon increases. This is accomplished by providing a roller 195 which rests on the roll of formed wire wound on the reel and which is slidably mounted in slots 196 and 197 formed in the legs 185 and 186 respectively. It will be apparent that as the diameter of the roll of formed wire increases, the roller 195 will be moved upwardly further away from the axes of the shafts 184 and 181. The means for rocking the yoke 75

is connected to the yoke by means of the roller, this being accomplished by projecting the shaft of the roller 195 beyond the leg 186. Rotatably journaled on the projecting end of this shaft is a sleeve 198 to which an arm 199 is connected, this arm carrying at its other end a loop 200 which carries a roller 201 which rides on a cam 202 mounted on the shaft 36. The cam is adapted to rock the yoke in the direction indicated by the arrow in Figure 13 of the drawings, there being provided a spring 203 connected to the standard 180 and to the arm 199 for returning the arm and thus the yoke to its original position. With the arm 199 connected to the yoke in this manner it will be apparent that as the diameter of the roll of formed wire increases the yoke will be rocked a lesser degree so that at all times the reel will be rotated just sufficiently to smoothly receive the formed wire.

For the purpose of removing the reel 170 when a sufficient quantity of formed wire has been wound thereon, the arm 185 of the yoke is hinged to the cross member 187 as at 205. A rotatable keeper 206 carried by the cross member 187, passes through the slot 196 in the arm 185 and may be rotated to a position such as shown in Figure 15 where the keeper will engage the outer face of the arm 185 to hold it in position as shown in Figure 12. Obviously, when it is desired to place a new reel on the shaft 181, the keeper 206 may be turned to the position shown in dotted lines in Figure 15 of the drawings at which time the arm 185 may be swung about its pivot 205 and the reel 170 removed from the shaft 181.

Before proceeding with an outline of the operation of the machine, it is to be noted that a platform or supporting table 210 is supported on the front of the machine by angle brackets 211 secured in any suitable manner to the frames 27 and 28. Secured to the plate or table 210, but spaced therefrom throughout the major portion of its length, is a strap 212 under which the wire passes to the forming drums.

It is to be noted further that each member 104 is provided with a slot 215 into which the lower end of the pin 151 moves during the last part of its oscillatory travel. Each member 104 further carries a block or cam 216 which engages the outer end of the adjacent jaw member when the jaws are moved outwardly as clearly illustrated in Figure 8 of the drawings. Shields 220 are provided, these shields being disposed over the members 90 as clearly illustrated in Figures 1, 2, 5 and 6 to prevent the wire from becoming disengaged from the pins 94. The forward ends of these shields are preferably flared upwardly to facilitate passage of the wire beneath the shields while the rear ends of the shields may be secured to the strap 132 as clearly illustrated in Figure 1 of the drawings.

Outlining now the operation of the machine, it will be understood by reference to Figure 2 of the drawings that upon each rotation of the shaft 36, the drums 56 and 57 will be indexed or rotatively moved a definite amount by the eccentric 42; each member 77 will be elevated momentarily by its respective cam 80, and the yoke associated with the receiving reel will be rocked by its cam 202. Further, during rotation of shaft 36, the shafts 125 will be driven to rotate the cam discs 123 to thus reciprocate the jaw members and to also rotate the disc 142 and thus oscillate the arm 130. It will be understood that the gears are so proportioned that the parts will be op-

erated in a definite sequence to obtain the desired results.

The wire to be formed is supplied to the machine from any suitable source (not shown), the source however, being preferably remote from the machine and located in substantial alignment with the longitudinal axis of the machine. The fact that the source of supply of the wire is remote from the machine provides that at the point where the wire is engaged by pin 151 on arm 10 130, the wire is relatively loose and may be bodily swung by the pin 151 without imparting any bending action to the wire. In fact the arrangement is such that the pin does not engage the wire 20 at all during the first half of the travel 15 of the wire from one side of the machine to the other, the pin engaging the wire at about the center of the machine and easily swinging it to the opposite side of the machine.

Referring now to Figure 1 of the drawings it 20 will be noted that the jaw members at the right hand side of the machine are in their innermost position and are crimping the wire about that pin on forming drum 57 which is at this instant in alignment with the path of reciprocation of 25 the jaw members. The forming drums are of course, stationary, and the arm 130 is moving to the left as viewed in this figure swinging the wire toward the drum 56. Pin A of drum 56, this pin being shown in Figures 1 and 4, has not as yet 30 been elevated by its respective member 77, the position of this pin with reference to its member 77 being more clearly illustrated in Figure 4. The arm 130 may therefore swing the wire over the pin A, the arm 130 continuing its travel until the 35 pin 151 thereof is elevated by the cam members 160 on the left of the machine to release the wire. Immediately prior to the raising of the pin 151 however, the member 77 associated with drum 56 is elevated by its cam 80 to thus elevate pin A 40 so that the wire is caught by this pin as soon as it is released by the pin 151. The next indexing movement of the drums which occurs immediately after this operation would move pin A to the position shown in Figure 3 of the drawings, 45 the pin at this time being in alignment with the jaw members and resting on the forward edge of cam surface 76. It will be understood that Figure 3 is a view of forming drum 57 but it will be apparent that the showing therein illustrates the 50 position which the pin A will assume when the drums are moved one step from the position shown in Figure 1 of the drawings.

As soon as the wire is released by the pin 151, the wire swings backwardly to the center of the 55 machine and the arm 130 starts its movement toward the right of the machine as viewed in Figure 1 of the drawings. The pin 151 of this arm engages the wire at about the center of the machine and swings the same to the right and over 60 pin B which at this time has been moved to the position shown in dotted lines in Figure 1 of the drawings, this position being designated by the reference character B'. It will be understood that when pin B is in the position of B' it bears 65 the same relation to its cam member 77 as the pin A bears to its cam member 77 in Figure 4 of the drawings.

This position of pin B and the position of the wire with reference to this pin is illustrated in 70 Figure 5 of the drawings, and by reference to this figure it will be noted first that the wire has passed over pin B and now lies beyond this pin. Further, the wire has passed under the forward end of shield 220 and is engaging one side of pin 94 and 75

the adjacent corner C of the adjacent jaw member. The corner C is notched as indicated at C' to loosely receive the wire and thus prevent the same from being elevated by raising of the pin 5 151. It might be noted that at this instant the wire would tend to swing the forward jaw member toward clamping position if it were not for the associated block 216 which prevents this undesired movement of the jaw member as clearly 10 illustrated in Figure 8 of the drawings.

Referring now again to Figure 5 of the drawings it will be understood that the pin B will now be elevated by its respective member 77 to a position to engage the wire when the latter is released by the raising of the pin 151. It will be noted further from this view that the pin 151 is just entering slot 215 and that cross arm 153 is about to be engaged by cam members 160 and pin 151 thus elevated. This elevation of pin 151 will release the wire, the body portion of the wire swinging back to the center of the machine but the adjacent portion being caught by the pin B which has now been elevated.

Immediately after this operation, the forming drums will be indexed one step to move pin B to the position shown in Figure 6 of the drawings, in which position it will be noted that this pin is in alignment with the path of reciprocation of the adjacent jaw members. The jaw members will 25 then be moved forwardly to bend the wire about pin B this gripping action of the jaw members being effected by the wedge member 110 associated with these jaw members.

The crimped or reversely bent portions of the 30 wire will be retained on the forming pins 70 as long as these pins are held in elevated position by the cam surfaces 76 of their respective cam members 75. Thus the formed wire will be maintained on the forming drums until the point of discharge is reached, this point being designated by the reference character D in Figures 1 and 3 of the drawings. It will be noted particularly by reference to Figure 3 that at point D the pins 66 ride off the cam surface 76 so that the forming 35 pins 70 are retracted to permit the formed wire to drop from the drums and into the chute 165.

Since, as brought out before, the forming reel is being rotated by a step by step movement and since the paper 172 is being wound thereon, it 40 will be apparent that the formed wire will be picked up and wound upon the receiving reel in the manner clearly illustrated in Figures 1 and 12 of the drawings. As the diameter of the reel of formed wire increases, the arc of oscillation of 45 the yoke associated with the reel will be varied by virtue of the raising of the roller 195. Thus the formed wire and the paper will be evenly wound on the receiving reel as will be clearly apparent.

From the above it will be apparent that the 50 invention provides a forming machine which will efficiently operate to provide desired bends in a wire at spaced points throughout the length thereof. By virtue of the fact that the portions of 55 the wire between the bent portions thereof are not subjected to bending stresses during operation of the machine it will be apparent that these straight portions of the wire will receive no partial set whatever and will thus be freely flexible.

It will be apparent further that the pins 94 being 60 engaged by the straight portions of the wire as clearly illustrated in Figure 5 of the drawings will limit bowing of these portions of the wire during the bending of the wire at one side of the machine and the swinging of the wire to the op-

posite side of the machine. The fact that the members 90 mounting the pins 94 are rotatively adjustable with reference to the forming drums provides that the pins 94 may be adjusted relative to the forming pins 70 to thus vary the 5 amount of bowing of the straight sections of the wire and thus the fullness of the straight sections of the wire.

Since the pins 70 must be accurately located with reference to the reciprocating jaw members, 10 and since further the pins on one drum must be accurately located with reference to the pins on the other drum, the invention provides for relative adjustment between each forming drum and its respective hub member 61. Further, since the 15 hub members may be adjusted longitudinally of shaft 40, it will be apparent that within certain limits the width of the strip of wire which is formed may be varied. For varying the degree of bending imparted to the wire, the wedge members 110 are adjustable to thus adjust the movement of the clamping portions of the jaw members toward each other. Further, since the forming pins 70 are readily removable from the pins 66 by virtue of their threaded connection to these 25 pins, it will be apparent that forming pins of different sizes and even of different shape may be readily substituted for those disclosed. The oscillation of the arm 130 with reference to the center of the machine as well as the length of the 30 arc of oscillation of this arm may be readily controlled by virtue of the turn buckle provided in the rod 140 and by virtue of the fact that this rod is adjustable radially of the disc 142 by virtue of slot 143.

It is an important feature of the machine that the formed wire is held on the pins 70 until these pins move a substantial distance away from the points where the wire is bent. By thus maintaining the formed wire on the forming drums for a 40 substantial time after the forming operation, danger of slipping of the formed wire about the pins is eliminated as is also the danger of pulling of the formed wire toward the point of forming. Thus the wire is not subjected to any strain which 45 might cause a set in the straight portions of the wire which has already been formed.

While the invention has been described with some detail, it is to be understood that the description is for the purposes of illustration only 50 and is not to be construed as limiting the scope of the invention. The right is reserved to make such changes in the details of construction and arrangement of parts as will fall within the purview of the attached claims.

What we claim as our invention is:

1. In a machine for forming bends in a wire at spaced points through the length thereof, forming members about which the portions of the wire to be bent are shaped, means for bending the 60 portions of the wire to be bent about said forming members, and additional means loosely engaging the wire for moving the portions of the wire to be bent into position to be engaged by said forming members and by said bending means 65 while maintaining the intermediate portions of said wire free from bending stresses.

2. In a machine of the class described, spaced forming members about which the portions of the wire to be bent are shaped, means for feeding a 70 length of wire to said forming members, and means between said forming members and engaging the wire for limiting bowing of the wire between said forming members during feeding and bending thereof.

3. In a machine of the class described, spaced bending mechanisms, means for feeding a length of wire to said mechanisms, and means associated with said bending mechanisms and adjustable relative thereto for limiting bowing of the wire between said bending mechanisms during feeding and bending thereof.
4. In a machine of the class described, spaced wire bending mechanisms, means for feeding a length of wire to said bending mechanisms, and pins disposed between said bending mechanisms and adjustable relative thereto for limiting bowing of the wire during feeding and bending thereof.
5. In a machine for forming bends in a wire at spaced points throughout the length thereof, a pair of bending mechanisms, means for alternately actuating said mechanisms, means for feeding alternate portions of the wire to be bent to one of said mechanisms and the other portions of the wire to be bent to the other of said mechanisms while maintaining the portions of said wire between the portions thereof to be bent free from bending stresses, and means for limiting bowing of the wire between said bending mechanisms.
6. In a machine of the class described, a forming drum, means for rotating said drum, means for moving a wire to be bent back and forth over said drum, forming members carried by said drum and movable into and out of the path of travel of the wire to be bent and means operating to move one of said forming members into the path of travel of the wire each time the wire is moved over the drum.
7. In a machine of the class described, a forming drum, means for moving a wire to be bent back and forth over said drum forming members carried by said drum and reciprocable radially thereof, means for rotating said drum, a movable cam arranged to move successively said forming members radially outwardly of said drum to cause the same to successively engage the wire, means operating to embrace each forming member while the same is in engagement with the wire to bend the wire about the forming members, and a stationary cam for holding said forming members in their outermost position during a portion of the rotation of the drum.
8. In a machine of the class described, spaced forming pin carrying members, means for moving said members in parallel planes, forming pins carried by said members, a wire bending means associated with each pin carrying member and arranged to successively embrace the pins carried thereby and means for swinging a wire to be formed alternately over said members for engagement with the forming pins carried thereby.
9. In a machine of the class described, spaced forming drums, means for rotating said drums with a step by step movement, an oscillating arm for swinging a wire to be formed alternately over said drums, pins carried by said drums adapted to engage the wire swung over the drums, and means for varying the length of the arc of oscillation of said arm.
10. In a machine of the class described, reciprocating clamping jaws, forming members adapted to be embraced by said jaws, means for feeding a wire to be formed into position to be engaged by said forming members, and means for moving said members to successively bring the same into the path of reciprocation of said clamping jaws.
11. In a machine of the class described, forming members about which portions of a wire to be formed are adapted to be bent, jaw members pivoted intermediate their ends adapted to embrace said forming members to bend the wire about the same, means for reciprocating said jaw members, and means for preventing movement of said jaw members to clamping position during the intervals that said jaw members are out of embracing relation with respect to said forming members.
12. In a machine of the class described, spaced forming drums, means for swinging a wire to be formed alternately over said drums, forming pins carried by said drums, means for rotating said drums, means for moving said pins radially outwardly of said drums to engage the wire swung over the same, forming jaws reciprocable relative to said drums, means for interrupting the movement of said drums each time a forming pin thereof is in alignment with the path of reciprocation of said forming jaws, and means carried by said drums for limiting bowing of said wire between said forming drums.
13. In combination, a machine for bending a wire at spaced points throughout the length thereof, a roll for receiving the strip of wire thus bent, means for rotating said roll to wind the wire strip thereon, and means for varying the speed of rotation of said roll in dependence upon the diameter of the coil of wire strip wound thereon.
14. In combination, a machine for forming bends in a wire at spaced points throughout the length thereof, a reel for receiving the strip of wire thus bent, means for rotating said reel to wind the strip of wire thereon, and means for feeding a strip of paper between the convolutions of the strip of wire wound on said reel.
15. In combination, a machine for forming bends in a wire at spaced points throughout the length thereof, a roll for receiving the strip of wire thus formed, a yoke associated with said roll for oscillation about the axis thereof, a pawl and ratchet connection between said yoke and said roll for moving the latter from the former, and means for varying the arc of oscillation of said yoke in dependence upon the diameter of the coil of wire wound on said roll.
16. In combination, a machine for forming bends in a wire at spaced points throughout the length thereof, a reel for receiving the strip of wire thus formed, a yoke associated with said reel for oscillation about the axis thereof, connections between said yoke and said reel for rotating the latter upon oscillation of the yoke, means associated with said wire bending machine for oscillating said yoke, and means for varying the extent of oscillation of said yoke in dependence upon the diameter of the roll of wire wound on said reel.
17. In a machine of the class described, a movable wire bending means, a forming member adapted to cooperate with said wire bending means to bend a wire, means for engaging said forming member with a wire to be bent, and means for moving said forming member to bring the wire into position to be acted on by said bending means upon movement of the latter.
18. In a machine of the class described, a forming member, clamping jaws adapted to embrace said forming member to bend a wire about the same, means for feeding a wire to be formed into position to be engaged by said forming mem-

- ber, and means for moving said forming member to bring the same into position to be embraced by the clamping jaws.
19. In a machine of the class described, a series of forming members, means for moving said forming members along a predetermined path, a wire bending means movable transversely of the path of movement of the forming members and adapted to embrace each forming member as the same is brought into alignment with its path of movement, and means for feeding a wire to be formed into engagement with said forming members.
20. In a machine of the class described, spaced forming drums, means for rotating said drums, means for swinging a wire to be formed alternately over said drums, forming members carried by said drums adapted to engage the wire swung over the drums, and means successively embracing the forming members on said drums to bend the wire about said forming members.
21. In a machine of the class described, spaced drums, means for swinging a wire to be formed alternately over said drums, forming members carried by said drums and arranged to engage the wire swung over the same, means for rotating said drums, and a wire bending means associated with each drum and adapted to successively embrace the forming members carried thereby to bend the wire about the same.
22. In a machine of the class described, spaced drums, forming pins carried by said drums, means for feeding a wire into engagement with said pins, means for rotating said drums, forming jaws reciprocal relative to said drums, and means for interrupting the movement of said drums each time a forming pin thereof is in alignment with the path of reciprocation of said forming jaws.
23. In a machine of the class described, spaced drums, an oscillating arm for swinging a wire to be formed alternately over said drums, forming pins carried by said drums adapted to engage the wire swung over the drums, means for rotating said drums, forming jaws reciprocal relative to said drums, means for interrupting the movement of said drums each time a forming pin thereof is in alignment with the path of reciprocation of said forming jaws, and means disposed between said drums and adjustable relative thereto for limiting the bowing of the wire between said drums.
24. In a machine of the class described, a series of forming pins, means for moving said series of forming pins along a definite path, means for moving a wire to be bent back and forth over the path of movement of the forming pins, and means for successively moving said pins in an axial direction into the path of movement of the wire whereby the pins are successively engaged by the wire.
25. In a machine of the class described, a forming drum, means for rotating said drum, forming pins carried by said drum and movable radially thereof, means normally maintaining said pins in their innermost position whereby a wire may be swung over said drum without contacting the pins, means for swinging a wire back and forth over the periphery of said drum, and means for successively moving said pins radially outwardly into the path of movement of the wire whereby said pins are successively engaged by the wire.
26. In a machine of the class described, a rotating drum, a series of pins carried by said drum for movement radially thereof, means for successively moving said pins radially outwardly upon rotation of the drum to cause the pins to successively project beyond the periphery of the drum, and means to bend a wire to be shaped about each pin after it has been projected beyond the periphery of the drum.
27. In a machine of the class described, a rotating drum, a series of pins carried by said drum for movement radially thereof, means for successively moving said pins radially outwardly upon rotation of the drum to cause the pins to successively project beyond the periphery of the drum, said means acting to maintain each pin projected during a portion of the rotation of the drum, means to bend a wire to be shaped about each pin after it has been projected beyond the periphery of the drum, and a shield arranged to maintain the shaped wire on the pins while they are projected.
28. In a machine of the class described, a rotating drum, a series of pins carried by said drum for movement radially thereof, means urging said pins radially inwardly of the drum, a stationary cam engaging the inner ends of said pins to hold each pin in its projected position during a portion of the rotation of the drum, means for bending a wire about each pin when it is in its projected position, and a shield so located as to retain the shaped wire on the pins while they are projected.
29. In a machine of the class described, a rotatable supporting means, two series of pins carried by said supporting means for movement radially thereof, the pins in one series being staggered with reference to the pins in the other series, means for successively moving said pins radially outwardly upon rotation of the supporting means to cause the pins to successively project beyond the periphery of the supporting means, said pin moving means being so arranged that one pin in one series is first moved outwardly and then the next pin in the other series is moved outwardly, and means to bend a wire to be shaped about each pin after it has been projected beyond the periphery of the supporting means.
30. In a machine of the class described, a rotating drum, a series of pins carried by said drum and projectable radially thereof, an oscillating arm movable over said drum, a finger carried by said arm and engageable with a wire to move the same over the drum to positions where the wire can be successively engaged by the pins, and means providing for vertical movement of said finger each time it moves the wire to a position to be engaged by one of said pins.
31. In a machine of the class described, a rotating drum, pins carried by said drum for movement radially thereof, an oscillating arm movable over the drum, a finger carried by the arm and engaging a wire to move the same over the drum, and means operating upon rotation of said drum to successively move said pins radially outwardly of said drum into positions whereby said pins successively engage the wire, said finger being mounted for vertical movement in the oscillating arm whereby it may move out of the plane of movement of the wire when the wire is engaged by the pin.
32. In combination, a machine for forming bends in a wire, a reel for receiving the strip of wire thus formed, a pawl and ratchet for rotating the reel, an arm mounted for oscillation and

carrying said pawl, a rod associated with the wire bending machine and adapted to be reciprocated thereby, and means connecting said rod to said arm in such a manner that reciprocation of said rod effects an oscillation of said arm, said means including a roller mounted for movement in a slot formed in said arm, and a connection be-

tween said roller and said rod, the roller being arranged to rest on the wire strip wound on said reel whereby as the diameter of the roll of wire wound on the reel increases the extent of oscillation of said arm is varied. 5
